MINE SKIP

Ora D. McClure, Ishpeming, Mich.

Application May 4, 1937, Serial No. 140,648

5 Claims. (Cl. 294—73)

This invention relates to a class of devices known as mine skips for hoisting and dumping ore, coal, and the like from mines and pits.

Such skips commonly comprise a frame or cradle to which the hoisting cable is attached, and a bucket in and pivotally connected at its lower end to the bottom of the cradle carrying the material to be hoisted. Suitable vertical guides are provided for the cradle and, at the top 5 of the pit, suitably curved guides are provided for engaging with the bucket and causing it to tilt and discharge its contents on the dump.

As heretofore built, the bucket consists of a square box which, with its cradle, fits in the shaft 13 of the mine or pit and is equipped with rollers on its top that engage a track at the dump that turns it upside down, discharging its contents. These skips are successful for handling dry material but, when raising soft and sticky ore and other like material, the ore will cling to and build 20 up in the corners of the box or bucket, and this building up in the corners extends up from the bottom and a large amount of the material is retained in the bottom of the skip which never 25 comes out. In soft ore mines, this sticking of the ore in the box or bucket gets so serious that periodically a man has to go inside and clean it out, resulting in delayed operations and other inconveniences.

One object of the present invention has been 30 to design a skip box or bucket of such a character that corners will be avoided and soft and sticky ore will discharge as freely as dry ore, practically the entire contents being discharged at each dumping operation.

Another object of the invention has been to provide in association with the hinge of the bucket 35 an improved system for automatically maintaining the hinge thoroughly lubricated so that the bucket will tilt easily at the dumping point.

Other objects have been to provide improvements in the cradle of the skip which will render 40 it more rigid, stronger, and more substantial.

Other objects and attendant advantages of the 45 invention will be apparent to persons familiar with devices of this character from the following detailed description taken in connection with the accompanying drawings in which I have illustrated an improved embodiment of the invention, 50 and wherein—

Fig. 1 is a longitudinal vertical section of the skip taken on the line 1—1 of Fig. 2.

Fig. 2 is a top plan view.

Fig. 3 is a bottom plan view.

Fig. 4 is a side elevation of the cradle.

Fig. 5 is an enlarged sectional view through one of the bearings of the bucket on the cradle, taken on the line 5—5 of Fig. 3.

Fig. 6 is an enlarged vertical section taken on the line 6—6 of Fig. 5.

Referring to the drawings, 10 designates as an 5 entirety the cradle, and 11 the bucket or box. More fully describing the cradle 10, this consists of a pair of vertical side members preferably consisting, as best shown in Fig. 4, of upper and lower 10 plates 12 and 13 and a plurality of angle bars 14 strongly riveted to and connecting said plates. The upper plates 12, as shown in Figs. 1 and 2, are integral with the ends of a one-piece cast metal 15 bail 15 formed with a central eye 16 for attachment of the hoisting cable. The lower plates 13 are steel castings formed with integral hollow 20 bosses 17 into which a pair of shafts 18 and 19 are pressed by hydraulic pressure to give a tight fit and rigidity to the cradle frame. Smooth 25 steel linings or shoes 20 are applied to the outer sides of the plates 12 (Fig. 2) and similar smooth linings 21 are applied to the inner angle bars 14 of the side frames, to afford a smooth and durable 30 sliding fit on the usual rectangular wooden uprights of the skip guides (not shown). Similar shoes or linings 20' and 21' are applied to the outer sides of the steel castings 13.

The bucket 11 is preferably formed by a main 35 body section 22 and a lower bottom section 23, both of rectangular cross section, and the lower section 23 is formed with an integral concave 40 parti-spherical bottom 24. The two sections are united by an external hoop or band 25 welded or otherwise secured to the meeting ends of the sections, other hoops or bands 26 being also employed 45 to stiffen and strengthen the body section 22. To eliminate corners of 90 degrees or less the corner portions of the bucket are beveled or chamfered as shown at 27 in Figs. 2 and 3. This rounding of 50 the bottom of the bucket and the beveling of its corners prevent soft or sticky ore from clinging to the interior of the bucket and greatly facilitate a clean dump of the ore as compared with the old and known square flat bottomed buckets. 55 On the upper end of the bucket are a pair of rollers 28 (Fig. 2) which, when the bucket reaches the top of the shaft, engage with suitably curved guides to effect the tilting and inversion of the bucket to dump the contents.

Integral with the cup-shaped bottom 24 of the bucket is a flange 29, to the bottom side of which is attached a pair of plates 30, and integral with each plate is a depending half bearing block 31 (Figs. 5 and 6) engaging the upper portion of the 55

shaft 19, with a lining section 32. To a flange 33 on the lower end of the half bearing block 31 is secured by screw bolts 34 an oil box 35, the top wall of which is formed with a mating half bearing 36 that engages the lower portion of the shaft 19 through a complementary half lining 37. The hollow box 35 provides a chamber 38 to contain a body of oil for lubricating the shaft bearing.

10 In the plate 30 and half bearing block 31 is a hole 39 that is normally closed by a plug 40. In the bottom of the hole 39 is a tapped hole 41 that receives the threaded upper portion of a tube 42 that extends downwardly through the chamber 38 into a hole 43 in the bottom wall of the chamber that is normally closed by a threaded plug 44. The lower end of the tube 42 is closed, and in the side wall thereof is a hole 45 through which the oil in the chamber enters the tube. In the bearing block 31 is a drilled duct 46, one end of which communicates with the hole 39 slightly above the open upper end of the tube 40, while its other end portion communicates with a radial duct 46' in the lining 37 through which the oil may flow to the surface of the shaft 19. Through the bottom portion of the lining section 37 and half bearing 36 is drilled a duct 47 through which the lubricant may drain back into the chamber 38.

30 The oil box 35 is attached to the half bearing block 31 not only by the screw bolts 34 but also, as shown in Fig. 5, by means of horizontal screws 48 that extend through end washers 49, annular flanges 50 on the ends of the linings 32 and 37, and into the ends of the block 31 and oil box 35.

When the contents of the bucket are dumped, the bucket tilts to the right or clockwise viewing Fig. 6, so that the oil in the tube 42 is caused to flow through the hole 39 and ducts 46, 46' to the top of the shaft bearing, thus maintaining the latter thoroughly lubricated, and when the bucket is upright surplus oil in the bearing drips back through duct 47 into the oil chamber 38. When it is necessary to refill or replenish the chamber 38, this is readily done by inverting the bucket, and withdrawing the plug 44.

It is believed that the foregoing description taken with the drawings will make clear to persons skilled in the art how the present invention 50 accomplishes the stated purposes and objects thereof. Variations and modifications in the structural details may be resorted to within the terms and scope of the appended claims.

I claim:

55 1. In a skip of the class described, the com-

bination of a bucket having a bowl-shaped bottom and an annular flange on the outer side of said bottom, a pair of axially aligned journal bearings attached to the bottom side of said flange, a cradle having at its lower end a pair of flat 5 steel end plates to which the lower end portions of the side limbs of the cradle are secured, and a pivot shaft for said bucket tightly fitted in holes in said end plates and rigidly connecting and spacing the latter, said pivot shaft extending 10 through said bearings.

2. In a skip of the class described, the combination of a cradle, a fixed shaft in and spanning the bottom of said cradle, and a bucket having on its bottom a bearing journaled on said shaft, said bearing having a hollow portion forming an oil chamber and an oil duct in said bearing leading from said chamber to said shaft and operative to conduct oil by gravity to said shaft only when said bearing is inverted. 15

3. In a skip of the class described, the combination of a cradle, a fixed shaft in and spanning the bottom of said cradle, and a bucket having on its bottom a bearing journaled on said shaft, said bearing having a hollow portion forming an oil chamber, an oil duct leading from said chamber to said shaft and operative to conduct oil by gravity to said shaft only when said bearing is inverted, and a return oil duct leading 20 from said shaft to said chamber. 25

4. In a skip of the class described, the combination of a cradle, a fixed shaft in and spanning the bottom of said cradle, and a bucket having on its bottom a bearing journaled on said shaft, said bearing having a hollow lower portion 35 forming an oil chamber, an oil duct leading from said chamber to the top portion of said shaft and operative to conduct oil by gravity to said shaft only when said bearing is inverted, and a return oil duct leading from the bottom portion 40 of said shaft to said chamber.

5. In a skip of the class described, the combination of a cradle, a fixed shaft in and spanning the bottom of said cradle, and a bucket having on its bottom a bearing journaled on said shaft, said bearing having a hollow lower portion 45 forming an oil chamber, an oil duct leading from said chamber to the top portion of said shaft and operative to conduct oil by gravity to said shaft only when said bearing is inverted, and a filling opening and removable closure therefor in the bottom of said oil chamber through which, by inverting said bucket, said chamber may be 50 charged with oil.

ORA D. McClure. 55
